UNITED STATES PATENT OFFICE.

THEODORE REGENSTEINER, OF CHICAGO, ILLINOIS.

PICTORIAL DISPLAY CARD.

Application filed October 20, 1924. Serial No. 744,620.

To all whom it may concern:

Be it known that I, THEODORE REGENSTEINER, a citizen of the United States, residing at Chicago, in the county of Cook and State of Illinois, have invented a new and useful Improvement in Pictorial Display Cards, of which the following is a specification.

My invention relates to an improved construction in the class of pictorial display cards, such as are designed for advertising purposes, including calendars, show-cards, window-cards, art novelties and the like; and the primary object of my invention is 10 to lend to the display on the card enhanced artistic effect.

I accomplish this and other objects by the construction hereinafter described and illustrated in the accompanying drawing, in 20 which—

Figure 1 is a face view of a calendar-bearing card having a pictorial display printed thereon and cut out about the outline to a base-line;

25 Figure 2 is a similar view of a picture-displaying sheet to be secured to the face of the card and with which the print of Fig. 1 is to be complementally associated;

Figure 3 is a similar view showing the 30 cut-out print of Fig. 1 on the card brought into complemental association with the picture presented in Fig. 2;

Figure 4 is an enlarged section on line 4-4, Fig. 3, showing parts somewhat exaggerated in thickness, and

35 Figures 5, 6 and 7 are views corresponding, respectively, with those presented in Figs. 1, 2 and 3, but showing my improvement applied to another pictorial display.

40 A card 8, which is preferably suitable cardboard and of the oblong rectangular shape shown, or of other desired shape, forms the background, which should be appropriately colored, for the picture to be displayed. The portion of such picture in Fig. 2, representing the incomplete figure of a woman, and in Fig. 6 a landscape, is printed on a separate sheet 9 of paper or other suitable material, and the sheet is

45 fastened, as by connecting it along its upper edge to hang therefrom and loosely cover the part of the background over which it extends. The complemental portion of the display-picture, such as the hands holding a 50 bouquet of flowers, represented at 15 in Fig. 1, or an automobile represented at 15^a in

Fig. 5, which is printed on the face of the card 8 (or may be a print cemented on that surface) is, preferably before affixing thereon the sheet 9, cut out, by die-cutting as a 60 matter of preference, about the outline to a base-line indicated at 10 in Figs. 1 and 5 which may be marked in the die-cutting operation and over which the free lower end of the sheet will reach. It is at this base-line 65 that the severed print remains attached to the card, which being flexible enables that portion to be there deflected or turned hinge-like forwardly into the position represented in Fig. 4, to permit the lower end of the sheet to be tucked behind it. This produces the complete-picture showing in Fig. 3, with the hand-held bouquet in complemental 70 position relative to the picture in Fig. 2, or that in Fig. 7 with the automobile of Fig. 5 75 in complemental position relative to the landscape of Fig. 7.

It is desirable, for enhancing the effect, to cause the cut-out print to stand out in relief; and for that purpose I provide, preferably in the cutting operation, a tab 13 to extend from the top of the print and bend it to a right-angle, as shown in Fig. 4, to bear against the face of the sheet 8.

I realize that considerable variation is 85 possible in the details of construction herein shown and described and I do not intend, by illustrating or describing a single specific embodiment of my improvement, to be limited thereto, it being my intention by the 90 appended claims to claim protection for all the novelty inherent in my invention as fully as the state of the art will permit.

I claim:

1. A pictorial display card having a portion partially severed therefrom to leave a straight flexible joining line at which it is bent outwardly from the card, said partially severed portion bearing a part of a picture, and a sheet secured at one end to the card and extending over the opening left therein by the portion partially severed therefrom and having its free end extending behind said partially severed and outwardly bent portion, said sheet containing a part of a picture complementing a part borne by said outwardly bent portion, whereby to present a view in relief of a complete picture.

2. A pictorial display card having a portion partially severed therefrom to leave a straight flexible joining line at which it is bent outwardly from the card, said partially

severed portion bearing a part of a picture, and a sheet secured at one end to the card and extending over the opening left therein by the portion partially severed therefrom and having its free end extending behind said partially severed and outwardly bent portion, said sheet containing a part of a picture complementing a part borne by said outwardly bent portion, whereby to present 10 a view in relief of a complete picture, and a tongue projecting from the free end of the partially severed portion to hold the same in its outwardly bent position.

3. A pictorial display-card having a picture secured thereon to hang over its face, a print cut about its outline out of said card in front of the picture to a base-line near the adjacent edge of said picture, and connecting the print to the card, said print being provided with a projecting tab and turned 20 on said connection to extend over a portion of said picture in complementary relation thereto, with the tab operating to project the print in relief.

THEODORE REGENSTEINER.
